HIGH SENSITIVITY AND POWER SIGNAL DETECTING DEVICE

Leon Riebman, Huntingdon Valley, and Frank E. McDonnell, Lansdale, Pa., assignors to American Electronic Laboratories, Inc., Colmar, Pa., a corporation of Pennsylvania

Filed June 4, 1965, Ser. No. 461,441
17 Claims. (Cl. 329—205)

ABSTRACT OF THE DISCLOSURE

The device comprises a plurality of semiconductor diodes connected in parallel, a first diode having a signal sensitivity greater than that of a second diode, while the second diode has a power handling capacity greater than that of the first diode. The first diode has a spreading resistance greater than that of the second diode while the second diode has a contact potential greater than the contact potential of said first diode, said combination of diodes providing a nonlinear voltage current characteristic, whereby the first diode handles a greater portion of the signal power than the second diode when the device receives signals at a first power level, while the second diode handles a greater portion of signal power when said device receives signals at a second power level greater than said first power level and without exceeding the power handling capability of the first diode of the device.

The invention relates to a signal detecting device, and more particularly to a device for detecting amplitude modulation of a signal and having high sensitivity and a high power handling capability.

Heretofore, video detector diodes have been available which are capable of providing excellent sensitivity when used in properly designed radio frequency and video circuits. Such diodes have not been capable of dissipating large amounts of radio frequency power without adversely altering their characteristics. Other diodes which are capable of dissipating large amounts of radio frequency power, however, are considerably less sensitive. Therefore, to date an undesirable compromise must be made between sensitivity and power handling capability. This fact is indicated in Table 1 below, which lists sensitivity, frequency and power handling ability.

TABLE 1

R.F. frequency (gc./sec.)	Peak power watts (.001 duty cycle, 1 k sec.)

8	61	49	48	47	43	42
10	60	47	46	45	42	41

On the other hand, the signal detecting device embodying the invention provides high sensitivity as well as high power handling capability as is indicated by the following Table 2.

2

The above Table 2 indicates the sensitivity and power handling characteristics of the signal detecting device for the present state of the art. However, with the development of higher sensitivity detectors, improvements can be directly incorporated into the signal detecting device of the present invention.

It is therefore a principal object of the invention to provide a new and improved signal detecting device for detecting amplitude modulation providing both high signal sensitivity and high power handling capacity.

Another object of the invention is to provide a new and improved signal detecting device for detecting amplitude modulation which is capable of providing increased sensitivity as developments occur which yield higher sensitivity detectors while still allowing the handling of high power without adversely altering the characteristics of the device.

Another object of the invention is to provide a new and improved signal detecting device of high sensitivity which will not be damaged by the application of high power, such as would result in burnout or adverse change in the characteristics of present art high sensitivity detector devices.

Another object of the invention is to provide a new and improved signal detecting device which may be readily fabricated using presently known techniques for producing high sensitivity diodes, and low sensitivity diodes with high power handling capability.

Another object of the invention is to provide a new and improved signal detecting device which is readily constructed, efficient in operation, and has a long operational lifetime.

The above objects as well as any other objects of the invention are achieved by providing a signal detecting device comprising first and second parallel connected semiconductor diodes in which the first diode has a signal sensitivity greater than that of the second diode while the second diode has a power handling capability greater than that of the first diode. The first diode also has a spreading resistance greater than that of the second diode, while the second diode has a contact potential and barrier resistance greater than the contact potential and barrier resistance respectively of the first diode.

The first diode handles a greater portion of the signal power than the second diode when the device receives signals at a first predetermined power level, while the second diode handles a greater portion of the signal power than the first diode when the device receives signals at a second predetermined power level greater than the first power level, without exceeding the power handling capability of the first diode.

The foregoing and other objects of the invention will become more apparent as the following detailed descrip-

tion of the invention is read in conjunction with the drawings, in which:

Like references designate like parts throughout the several views.

Refer to FIGURE 1 which schematically illustrates a signal detecting device 10 embodying the invention,

The device 10 has a pair of terminals A and B between which are connected in parallel a first high sensitivity semiconductor diode D₁, and a second semiconductor diode D₂ having high power handling capability. The diode D₂ although having high power handling capability does not have the high sensitivity characteristic provided by the diode D₁, while the diode D₁ although provided with a high sensitivity, does not have the power handling capabilities of diode D₂. In this connection, it is noted that point contact semiconductor diodes provides the high sensitivity and low power handling capabilities of the diode D₁, while junction diodes provide the characteristic of low sensitivity and high power handling capability characterizing diode D₂.

The diode D₁ is further characterized by having a spreading resistance greater than the spreading resistance of the diode D₂, while the high powered or parasitic diode D₂ has a contact potential and barrier resistance greater than the contact potential and barrier resistance respectively of the diode D₁. The above properties for diodes D₁ and D₂ may also be provided respectively by point contact and junction diodes. The further detailed relationships between the spreading resistance and contact potentials of the diodes D₁ and D₂ for the purpose of the

invention will be described below in connection with FIGURES 3 to 6 inclusive.

FIGURE 2 schematically illustrates the equivalent circuit for the circuit of the signal detecting device 10 shown in FIGURE 1. Thus, the high sensitivity diode D₁ includes a barrier resistance R₁ which varies as a function of the potential applied across the diode D₁. The capacitance C₁ shown in parallel with the barrier resistance R₁, represents the barrier capacitance of the diode D₁. The spreading resistance of r_{S1} of the diode D₁ is connected in series with the parallel connector barrier resistance R₁ and barrier capacitance C₁ and includes the resistance of the semiconductor material.

The high power or parasitic diode D₂ has an equivalent circuit similar to the semiconductor diode D₁, including a barrier resistance R₂ which varies with the voltage applied across the diode D₂ and a barrier capacitance C₂ connected in parallel therewith, as well as a spreading resistance r_{S2} connected in series therewith.

FIGURE 3 illustrates in graphic form the current voltage characteristic of high sensitivity diode D₁ with the application of voltage across the terminals A and B in the forward direction of the diode D₁. The curve 12 of FIGURE 3 comprises a first portion 14 produced when the voltage is less than the contact potential ϕ_1 of the diode D₁, and a second portion 16 of greater slope characterizing the current flow when the applied forward voltage exceeds the contact potential ϕ_1 . The slope of the portion 16 of the curve 12 is inversely related to the spreading resistance r_{S1} of the diode D₁.

The high power diode D₂ as seen from FIGURE 4 is characterized by a curve 18 illustrating the current voltage characteristic for the application of voltage in forward direction across the diode D₂. The curve 18 also provides a portion 20 of low current, characterizing the high resistance of the diode D₂ for voltages below the contact potential ϕ_2 of the diode D₂. The second portion 22 of the curve 18 illustrates the current characteristic when the voltage exceeds the contact potential ϕ_2 . The slope of the portion 22 is inversely related to the spreading resistance r_{S2}. Thus, from the graphic illustrations it is evident that the contact potential ϕ_1 of the diode D₁ has a lower value than the contact potential ϕ_2 of the high power diode D₂. By the portions 14 and 20 respectively of graphs 12 and 18 of FIGURES 3 and 4, the diode D₁ is illustrated as having a lower barrier resistance than the diode D₂ and to dissipate a higher portion of the current delivered to the signal detecting device 10 when the voltage V is less than the contact potential ϕ_2 . A comparison of the slopes of the portion 16 and 22 respectively of the curves 12 and 18 in FIGURES 3 and 4 also illustrates the spreading resistance r_{S1} of diode D₁ to have a greater value of resistance than the spreading resistance r_{S2} of the high power diode D₂.

FIGURE 5 illustrates graphically the total current versus voltage characteristic of device 10 with the voltage applied in the forward direction to the device 10 combining the characteristics illustrated by the graphs of FIGURES 3 and 4. The portion 21 in the curve 19 illustrates the current voltage characteristic of the device 10 for applied voltages having values less than the contact potential ϕ_1 of the diode D₁, while the portion 23 shows the characteristic of the device 10 for applied voltages having values between the contact potential ϕ_1 and ϕ_2 of the diodes D₁ and D₂. For high power signals in which the applied voltage to the device 10 exceeds the contact potential ϕ_2 of the diode D₂, the portion 25 illustrates the low spreading resistance provided by the diode D₂ for dissipating a greater portion of the power dissipated by the device 10 and preventing the burn out of the high sensitivity low power diode D₁.

Qualitatively describing the operation of the signal detecting device 10, when a signal such as a radio frequency signal having low power is delivered to the terminals A and B of the device 10, a power division takes place be-

tween the diodes D_1 and D_2 with a current i_1 of the total current i delivered to the device 10 being received by the diode D_1 while a current i_2 flows through the high power or parasitic diode D_2 . At this time, to obtain a most efficient operation of the device 10 maximum current should be delivered through the high sensitivity diode D_1 , while current through diode D_2 should be minimized. As illustrated by the graphs of FIGURES 3 and 4 with the radio frequency power delivering signal voltages less than the contact potential ϕ_2 of the parasitic high power diode D_2 , a greater portion of the current i flows through the high sensitivity diode D_1 , while a smaller fraction of the total current passes through the parasitic diode D_2 for providing high efficiency during receipt of low power signals.

When a high power signal is received by the device 10 its application to terminals A and B provides a voltage exceeding contact potential ϕ_2 of the high power diode D_2 . Since the parasitic diode D_2 has lower spreading resistance than the high sensitivity diode D_1 this results in diode D_2 conducting therethrough a greater portion of the total current i . Thus, the parasitic diode D_2 operates to dissipate a greater proportion of the power dissipated by the device 10 limiting the power dissipated by the high sensitivity diode D_1 and thereby protecting same against burnout or undesirable alteration of its characteristics.

The following theoretical explanation of the operation of the signal detecting device 10 may be divided into the theory of low level power division for determining the sensitivity of the device 10, and the theory of high level power division for establishing the burnout characteristics of the device 10.

In considering the theory of low level power division, a first approximation is helpful in which the device 10 is analyzed as a combination of two parallel diodes including the high sensitivity diode D_1 and the high power parasitic diode D_2 as illustrated in FIGURE 1, in which the diode D_1 may be considered a point contact diode and diode D_2 is a junction diode. The expression for current through a point contact or junction diode may be expressed as a function of the voltage applied across its external terminals A and B by the following equation:

$$i = I_0 e^{-\alpha(V - ir_s)} - 1 \quad (1)$$

in which i and V are respectively the terminal current and voltage; α is a constant proportional to q/KT ; I_0 is a constant of proportionality; r_s is the series resistance of the device exclusive of the barrier resistance and is commonly referred to as the spreading resistance; and ϕ is the contact potential of the diode under consideration.

Radio frequency power P , incident on the device 10 at its terminals A and B, causes a current $i = i_1 + i_2$ to flow, with a power division proportional to the current division according to the following equation:

$$P_{in} = V_0 i = V_0 (i_1 + i_2) \quad (2)$$

Assuming that the spreading resistance r_{s1} of the diode D_1 is equal to 200 times the spreading resistance r_{s2} of the diode D_2 where the spreading resistance of the diode D_2 has a value of one ohm, the Equation 2 gives the following expressions:

$$i_1 = I_0 e^{-\alpha\phi_1} [e^{\alpha(V_0 - i_1 200)} - 1] \quad (3a)$$

$$i_2 = I_0 e^{-\alpha\phi_2} [e^{\alpha(V_0 - i_2)} - 1] \quad (3b)$$

The ratio of the currents i_1 and i_2 respectively through the diodes D_1 and D_2 provides an expression for the ratio of power dissipated by the respective diodes D_1 and D_2 as follows:

$$\frac{i_1}{i_2} = \frac{I_0}{I_0} e^{\alpha(\phi_2 - \phi_1)} \left[\frac{e^{\alpha(V_0 - i_1 200)} - 1}{e^{\alpha(V_0 - i_2)} - 1} \right] \quad (4)$$

Using the approximation where

$$[e^{\alpha(V - ir_s)} - 1] \approx \alpha(V - ir_s) \approx \alpha V$$

under restriction that ir_s is much less than V_0 , the above Equation 4 reduces to the following expression:

$$\frac{i_1}{i_2} \approx \frac{I_1}{I_2} e^{\alpha(\phi_2 - \phi_1)} \quad (5)$$

The above approximation is justified by considering a typical diode such as type AEL-12 of American Electronic Laboratories, Inc., where V_0 at the operating point is approximately .25 volt, r_s is approximately equal to 200 ohms, and i is approximately equal to 5×10^{-6} amps.

If we define P_1 equal to $i_1 V_0$, P_2 equal to $i_2 V_0$ and λ equal to P_1/P_2 , then:

$$\lambda = \frac{I_1}{I_2} e^{\alpha(\phi_2 - \phi_1)} \quad (6)$$

There are two major points to consider when interpreting the above equation with respect to the physics of the device 10 which are as follows:

(a) The leakage current of the parasitic diode D_2 should be small relative to the leakage current of the high sensitivity diode D_1 of the signal detecting device 10, and,

(b) The contact potential ϕ_2 of the parasitic diode D_2 should be as large as possible, and the contact potential ϕ_1 of the high sensitivity diode D_1 should be as small as possible to achieve the desired sensitivity characteristic.

When burnout of the sensitive diode D_1 of the device 10 is considered, there is a restriction on how large λ can be made. If λ is too large, then, before the parasitic or high power diode D_2 can absorb an appreciable amount of incident power, thus providing protection for the high sensitivity diode D_1 , the diode D_1 is burned out.

One method of obtaining a large λ , as evidenced by Equation 8, is to increase the difference $(\phi_2 - \phi_1)$. This can be accomplished either by making ϕ_2 large, ϕ_1 small, or both. However, in view of the burnout considerations discussed above, there must be an upper limit placed upon the magnitude of $(\phi_2 - \phi_1)$.

As a first approximation in determining this limiting value, make the following assumptions:

$$i = 0 \text{ for } V < \phi \quad (7a)$$

$$i = \frac{V - \phi}{r_s} \text{ for } V > \phi \quad (7b)$$

Under the above conditions and assumptions the respective currents are given as follows for diodes D_1 and D_2 :

$$i_1 = \frac{V - \phi_1}{r_{s1}} \quad (8a)$$

$$i_2 = \frac{V - \phi_2}{r_{s2}} \quad (8b)$$

Consider FIGURE 6 in which the above equation for i_1 is given by the line 24 having a slope equal to the reciprocal of the spreading resistance r_{s1} of diode D_1 . The line 26 in the graph FIGURE 6 also represents the equation for i_2 and has a slope equal to the reciprocal of the spreading resistance r_{s2} of the diode D_2 .

Considering a typical junction diode for the parasitic or high power diode D_2 , such as type AEL-30E of American Electric Laboratories, Inc., rated at one watt with a spreading resistance r_{s2} equal to approximately one ohm then:

$$P_2 = (i_2)^2 r_{s2} = \frac{(V - \phi_2)^2}{r_{s2}} = 1 \text{ watt} \quad (9)$$

Since r_{s2} , the spreading resistance of D_2 , is equal to one ohm,

$$(V - \phi_2) = 1 \text{ volt}$$

Considering a typical point contact diode for the high sensitivity diode D_1 such as the type AEL-12 of American

Electronic Laboratories, Inc., rated for .2 watt with a spreading resistance r_{S1} equal to 200, then

$$P_1 = (i_1)^2 r_{S1} = \frac{(V - \phi_1)^2}{r_{S1}} \quad (10)$$

Since the spreading resistance $r_{S1} = 200$ ohms and $V = 1 + \phi_2$,

$$(\phi_2 - \phi_1) = 5.3 \text{ volts}$$

Under the worst case assumption in which P_1 equals P_{total} at $i_2 \leq i_1$ the maximum power in diode D_1 is

$$P_1 \leq \frac{\phi_2^2}{r_{S1}} = 0.140 \text{ watts if } \phi_1 = 0 \quad (11)$$

Thus it is possible to specify a safe value of $(\phi_2 - \phi_1)$ equal to or less than 5.3 volts for the particular diodes D_1 and D_2 under consideration in the above example.

On physical considerations the contact potential ϕ_1 of the diode D_1 can be made to approach zero by appropriate choice of metal-semiconductor interface material. Then one of the largest contact potentials in a semiconductor available at present, useful at room temperatures, is found in gallium phosphide, having 2.2 ev. This does not preclude using high ϕ materials, but merely indicates that all materials available today are within the theoretical limit established for $(\phi_2 - \phi_1)$. These conditions are represented graphically by FIGURES 3, 4 and 5 considered above.

The threshold sensitivity P_{ST1} (in $-\text{dbm}$) is related to the power P_1 in watts dissipated by the diode D_1 by the following expression:

$$P_{ST1} = 10 \log_{10} \frac{P_1}{10^{-3}} \quad (12)$$

Then, including the sensitivity degradation due to the parasitic diode D_2 , the resultant threshold sensitivity of the device 10 may be determined by using the following equation:

$$P_{ST1} (-\text{dbm}) = 10 \log_{10} \frac{P_1}{10^{-3}} \left(1 + \frac{1}{\lambda} \right) \quad (13)$$

Considering now the power handling capability of the signal detecting device 10, when high power is incident on the device 10 in the forward direction, the effective impedance of each diode D_1 and D_2 under such conditions is its respective spreading resistance r_{S1} and r_{S2} as illustrated schematically in the equivalent circuit of FIGURE 7 for the device 10. If the voltage V_o is applied to the terminals A and B of the device 10, then the total power which must be dissipated by the device 10 is:

$$P_T = \frac{V_o^2 (r_{S1} + r_{S2})}{r_{S1} r_{S2}} \quad (14)$$

The power in each diode D_1 and D_2 of the device 10 follows from the above equation as

$$P_T = P_1 + P_2 = \frac{V_o^2}{r_{S1}} + \frac{V_o^2}{r_{S2}} \quad (15)$$

Experimental evidence indicates that in connection with a typical high sensitivity diode D_1 such as the type AEL-12, the typical average power which the spreading resistance r_{S1} can dissipate without adversely altering the diode characteristics is 200 mw. and the peak power is 5 watts, with a one microsecond pulse width and a .001 duty cycle.

To determine the relationship between spreading resistance r_{S1} and the spreading resistance r_{S2} respectively of the diode D_1 and D_2 to permit the signal detecting device 10 to safely handle 1000 peak watts, let

$$r_{S2} = \delta r_{S1} \quad (16)$$

Then by substituting this relationship in Equation 14 above gives:

$$P_T = \frac{V_o^2 (1 + \delta) r_{S1}}{\delta r_{S1}^2} = \frac{V_o^2}{r_{S1}} \frac{(1 + \delta)}{\delta} = 1000 \text{ watts} \quad (17)$$

Since the high sensitivity diode D_1 can only handle five peak watts

$$P_1 = \frac{V_o^2}{r_{S1}} = 5 \text{ watts} \quad (18)$$

and

$$P_T = 1000 \text{ watts} = \frac{5(1 + \delta)}{\delta} \quad (19)$$

Under these conditions

$$\delta \approx \frac{1}{200} \quad (20)$$

and

$$r_{S1} = 200 r_{S2} \quad (21)$$

This justifies the assumption made in connection with Equations 3a and 3b. The diode characteristic corresponding to the conditions of Equation 6 and Equation 21 are indicated in FIGURES 3, 4 and 5.

Consider now FIGURES 8 and 9 which illustrate a practical embodiment of the signal detecting device 10. The signal device 10 comprises a base portion 28 made of a highly conducting metallic material such as provided by a copper base alloy providing an extending cylindrical section 30 and a top base plate 32. A cylindrical wall portion 34 which may be made of a ceramic material having high electrical insulating properties is hermetically sealed with the base plate 32 of the base portion 28 to provide an internal chamber 36. The top 38 of the wall section 34 is hermetically sealed to a ring member 40 which is made of a highly conducting material such as the material of the base portion 28. A semiconductor substrate which may be highly doped silicon to provide a high acceptor concentration is joined to the base plate 32 by a nickel gold alloy 44 providing a good ohmic contact between the substrate 42 and the base portion 28. An epitaxial film 46 may be deposited on the substrate 42 from a vapor phase in the well-known manner. The epitaxial film 46 may be of silicon material having a resistivity higher than that of the substrate 42 and a lower acceptor carrier concentration. A second epitaxial film 48 may be deposited on the substrate 42 at the same time film 46 is deposited but at a different location from the epitaxial film 46, with the film 48 being identical in composition and characteristics to the epitaxial film 46. A diffused or alloyed N type region with a high barrier resistance is provided at the layer of material 50 over the P type layer of material of film 48, as provided by well-known techniques.

In order to provide the high sensitivity contact diode D_1 , an electrically conductive wire or lead 52 is positioned with its end 54 in contact with the epitaxial film 46. The lead 52 is retained in contact with the film 46 by the epoxy material 56. This provides a point contact diode D_1 having high sensitivity but limited in its power handling capabilities.

A second conductive wire or lead 58 has its end 60 positioned in contact with the region or layer of material 50 by epoxy material 62 for providing with the epitaxial film 48 a junction diode D_2 characterized by its low sensitivity and high power handling capabilities.

The ends 64 and 66 respectively of the leads 52 and 58 are electrically connected with the ring 40 and the chamber 36 is hermetically sealed by the welding of a conductive metallic top plate 68 about its periphery 70 with the conductive ring 40. If desired the chamber 36 may be filled with a potting compound in addition to being hermetically sealed.

The form of the signal detecting device 10 illustrated in FIGURES 8 and 9 provides better performance by including the diodes D_1 and D_2 in an integrated structure and within the unitary enclosure by preventing variation 75 in parasitics which might otherwise be prevalent. Of

course, the above is a particular example of the structure of the device 10, however, the signal detecting device 10 may be fabricated in various other forms to provide the advantages of high sensitivity and high power handling capacity.

FIGURE 10 schematically illustrates a signal detecting device 72 which is a modification of the device 10 shown in FIGURE 1. In the illustrated form of device 72, a high sensitivity diode 74 is connected between terminals 76 and 78 of the device, while a high power handling diode 80 is connected in parallel therewith. The diode 74 and diode 80 have the same relative characteristics as the diodes D₁ and D₂ of the device 10. Thus, the diode 80 has a higher barrier resistance than the diode 74 as well as a higher contact potential, while the diode 74 has a higher spreading resistance than the diode 80.

In order to allow for greater dissipation of power than afforded by the device 10, an additional high power diode 82 is connected in parallel with diodes 74 and 80 and has a contact potential greater than the contact potential of the diode 80 and a spreading resistance which is of lower value than that of the diode 80. Similarly a diode 84 is also connected in parallel with the diodes 74, 80 and 82 and is a high power handling type device with a contact potential greater than the contact potential of the diode 82 and a spreading resistance of lower value than that of the diode 82. The barrier resistance of the combined parallel connected diodes 80, 82 and 84 has a value greater than the barrier resistance of the high sensitivity diode 74, so that the device 72 operates at high efficiency when low power signals are being detected by the device 72. The device 72 thus provides means whereby signals with power greater than those which can be handled by the device 10 may safely be handled without destruction of the high sensitivity diode 74 of the device 72.

The signal detecting device 86 schematically illustrated in FIGURE 11 is a modified form of the device 10 shown in FIGURE 1 and is most useful when handling high peak level radio frequency signals where burnout due to avalanche current following back breakdown is the problem.

In the device 86 a high sensitivity diode 88, such as the point contact type is connected between terminals 90 and 92, while a high power diode 94, which may be of the junction type is connected in parallel therewith. A second high power handling type diode 96 is connected in antiparallel with the diodes 88 and 94. Thus, while the anodes on the diodes 88 and 94 are connected to the terminal 90, the cathode of the diode 96 is connected to the terminal 90 and its anode is connected with the cathodes of the diodes 88 and 94 to the terminal 92.

The curve 98 of FIGURE 12 graphically illustrates the current voltage characteristic of the high sensitivity diode 88, while the curve 100 of FIGURE 13 illustrates the like characteristic for the high power diode 94. The curve 102 illustrates the current voltage characteristic of the antiparallel connected diode 96, while the curve 104 of FIGURE 15 provides the total current voltage characteristic for the device 86. The high current handling capabilities of the diodes 94 and 96 are respectively indicated at the end portions 106, 108 of the curve 104 for providing the device 86 with high power handling capabilities under reverse breakdown conditions.

It will be obvious to those skilled in the art that the invention may find wide application with appropriate modification to meet the individual design circumstances, but without substantial departure from the essence of the invention.

What is claimed is:

1. A signal amplitude modulation detecting device comprising first and second parallel connected operatively independent semiconductor diodes, the first diode having a signal sensitivity greater than that of said second diode while said second diode has a power handling capacity

greater than that of said first diode, said combination of diodes providing a nonlinear voltage characteristic.

2. The device of claim 1 in which said first diode has a spreading resistance greater than that of said second diode.

3. The device of claim 1 in which said second diode has a contact potential and barrier resistance greater than the contact potential and barrier resistance respectively of said first diode.

10 4. The device of claim 1 in which said first diode has a spreading resistance greater than that of said second diode and said second diode has a contact potential and barrier resistance greater than the contact potential and barrier resistance respectively of said first diode.

15 5. The device of claim 4 in which said first diode handles a greater portion of signal power than said second diode when said device receives signals at a first predetermined power level, while said second diode handles a greater portion of signal power than said first diode when said device receives signals at a second predetermined power level greater than said first power level and without exceeding the power handling capability of said first diode.

20 6. A signal amplitude modulation detecting device comprising first and second semiconductor diodes each characterized by the following expression for current as a function of voltage applied across its external terminals

$$i = I_0 e^{-a\phi} [e^{a(V_0 - ir_s)} - 1]$$

25 30 where i , V_0 are the terminal current and voltage respectively, a is constant proportional to q/KT , I_0 is a constant of proportionality, r_s is the series resistance of the device exclusive of the barrier resistance, and ϕ is the contact potential; said first and second diodes being operatively independent and connected in parallel and said second diode having a power handling capability greater than that of the said first diode.

35 7. The device of claim 6 in which said first diode has a resistance r_{s1} greater than the resistance r_{s2} of said second diode.

40 8. The device of claim 6 in which said second diode has a contact potential ϕ_2 and barrier resistance R_2 , greater than the contact potential ϕ_1 and barrier resistance R_1 respectively of said first diode.

45 9. The device of claim 6 in which said first diode has a resistance r_{s1} greater than the resistance r_{s2} of said diode and said second diode has a contact potential ϕ_2 and barrier resistance R_2 greater than the contact potential ϕ_1 and barrier resistance R_1 respectively of said first diode.

50 10. The device of claim 9 in which in which the differential between the contact potentials of said second and first diodes ($\phi_2 - \phi_1$) has a value equal to or less than a predetermined maximum value so that said first diode handles a greater portion of signal power than said second diode when said device receives signals at a first predetermined power level, while said second diode handles a greater portion of signal power than said first diode when said device receives signals at a second predetermined power level greater than said first power level and without exceeding the power handling capability of said first diode.

55 11. A signal amplitude modulation detecting device comprising a first semiconductor diode and a plurality of second semiconductor diodes connected in parallel, said first diode being operatively independent from and having a signal sensitivity greater than those of said second diodes while said second diodes each having a different power handling capability which is greater than that of said first diode.

60 12. The device of claim 11 in which each of said second diodes has a different spreading resistance and said first diode has a spreading resistance greater than that of any one of said second diodes.

65 13. The device of claim 12 in which each of said second

diodes has a different contact potential and said first diode has a contact potential and barrier resistance less than the contact potential and barrier resistance respectively of any one of said second diodes.

14. The device of claim 13 in which said first diode handles a greater portion of signal power than said second diodes when said device receives signals at a first predetermined power level, while said second diodes handle a greater portion of signal power than said first diode when said device receives signals at a second predetermined power level greater than said first power level and without exceeding the power handling capability of said first diode, power being shared among said second diodes at levels between said first and second power levels depending upon their respective values of contact potential, barrier resistances and spreading resistances.

15. A signal amplitude modulation detecting device comprising a first semiconductor diode, a second semiconductor diode connected in parallel with said first semiconductor diode, and a third semiconductor diode connected in antiparallel to said first diode being operatively independent from and, said first diode having a signal sensitivity greater than those of said second and third diodes while said second and third diodes each have a

power handling capability which is greater than that of said first diode.

16. The device of claim 15 in which said second and third diodes each have a spreading resistance less than that of said first diode.

17. The device of claim 16 in which said second and third diodes each have a contact potential and barrier resistance greater than that of said first diode.

UNITED STATES PATENT OFFICE
CERTIFICATE OF CORRECTION

Patent No. 3,418,587

Dated December 24, 1968

Inventor(s) L. Riebman, et al.

It is certified that error appears in the above-identified patent and that said Letters Patent are hereby corrected as shown below:

Column 1, line 52, in TABLE 1, "Peak power watts (.001 duty cycle, 1 k sec.)"
should read --Peak power watts (.001 duty cycle, 1 μ sec.)--. Column 2,

line 3, in TABLE 2, "Peak power watts (.001 duty cycle, 1 k sec.)" should
read --Peak power watts (.001 duty cycle, 1 μ sec.)--. Column 5, line 42,

equation (1) should read -- $i = I_0 e^{-\alpha\theta} [e^{\alpha(V_0 - ir_s)} - 1]$ --. Column 5, line 61,
equation (3a) should read -- $i_1 = I_1 e^{-\alpha\theta_1} [e^{\alpha(V_0 - i_1 200)} - 1]$ --. Column 5,

line 63, equation (3b) should read -- $i_2 = I_2 e^{-\alpha\theta_2} [e^{\alpha(V_0 - i_2)} - 1]$ --.

Column 6, line 2, equation should read -- $[e^{\alpha(V - ir_s)} - 1] \approx \alpha(V_0 - ir_s) \approx \alpha V_0 -$

Column 10, line 28, equation should read -- $i = I_0 e^{-\alpha\theta} [e^{\alpha(V_0 - ir_s)} - 1]$ --.
